DISPLAY OR STORAGE CABINET

John E. Echlin, New Haven, Conn., assignor to
Beryl G. Echlin, New Haven, Conn.

Application March 27, 1945, Serial No. 585,084

5 Claims. (Cl. 211—136)

1

This invention relates to storage or display cabinets, and more particularly to a device of this character adapted to receive and contain for storage or display, or both, relatively small objects either in boxed or unboxed form. The cabinet is also, of course, applicable to objects or boxes of large size, but, as disclosed, it is intended particularly for division into a large number of compartments, these compartments being arranged in rows or tiers, each row of compartments being characterized as a shelf. The size of the objects which the cabinet may be arranged to accommodate will, of course, depend upon the vertical spacing of the rows or shelves and the number of compartments in each row or, in other words, the number of divisions provided upon each shelf.

In general, the device, as illustrated, comprises an open cabinet comprising end walls or supporting members between which extend the plurality of shelves or rows of compartments. These shelves, as illustrated, consist of a pair of stringer elements, which stringer elements may be secured to the end supports or may be, as illustrated, secured together at their ends to form a rectangular frame, and this frame secured to the end supports either rigidly or for tilting movements as desired.

To form the compartments on the shelves, a plurality of hanger members or brackets are employed. These brackets are, as shown, of substantially L-shaped form and consist of flat sheet metal stock, the ends of which will be secured or engaged in a satisfactory manner with the pair of stringer elements forming a shelf. The stringer elements are not only spaced from front to back but are also spaced one above the other, so that each end of one of the bracket members may be secured to one of the stringers.

Preferably the brackets may be engaged at any desired adjusted position along the length of the stringers so as to form divisions or compartments of any desired width without it being necessary to conform to any standard, so that compartments can be formed along each shelf of the proper width to accommodate the box or package regardless of the dimensions of the latter.

As will be apparent as the description proceeds, these hanger members or brackets are of two kinds, one having a flange projecting outwardly from its body portion, the flange here forming a partition or division between two adjacent compartments or being adapted to detachably receive a separate partition member forming the divi-

2

sion between the two compartments. The body portions of the brackets will form ledges at each side of a compartment upon which boxes or packages may rest, or if it is desired to employ the cabinet in connection with loose articles of small size, to form ledges upon which plates may rest to form the bottoms and backs of bins for unboxed items.

One object of the invention is to provide a display or storage cabinet which may be economically manufactured principally from sheet metal parts of small size, so that scrap may be employed in its manufacture if desired.

A further object of the invention is to provide a storage or display cabinet which may be economically made from a relatively small number of parts, so arranged that they may be readily assembled by an unskilled person without the use of special tools whereby the cabinets may be shipped in knocked-down condition and assembled after their receipt by the purchaser.

A still further object of the invention is to provide a display or storage cabinet having a plurality of shelves or tiers of compartments, the compartments being formed by adjustable members so arranged that they may be given any desired spacing to form compartments of any desired width.

A still further object of the invention is to provide a storage or display cabinet of the character described such that the spacing of the members forming the compartments may be changed or adjusted at will by the user without the necessity of special tools.

A still further object of the invention is to provide a storage or display cabinet which may be economically manufactured and which will contain a large number of relatively small parts or boxes or packages within a compact space by means of the compact arrangement of a relatively large number of different compartments for packages of merchandise of assorted kinds.

To these and other ends the invention consists in the novel features and combinations of parts to be hereinafter described and claimed.

In the drawings:

Fig. 1 is a front elevational view of a cabinet embodying my improvements;

Fig. 2 is a sectional view on line 2—2 of Fig. 1;

Fig. 3 is an enlarged sectional view of one of the shelves or rows of compartments in the cabinet;

Fig. 4 is a perspective view of the left-hand hanger member or bracket;

Fig. 5 is a perspective view of the right-hand hanger member or bracket;

Fig. 6 is a perspective view of the flat dividing or partition member;

Fig. 7 is a perspective view of the angle-shaped plate member forming the bottom and back of the bins;

Fig. 8 is an enlarged sectional view showing one method of securing the brackets upon the stringer elements;

Fig. 9 is a front view of the parts shown in Fig. 8;

Fig. 10 is a view of the locking elements for locking the brackets in place;

Fig. 11 is a sectional view showing another method of holding the brackets in place upon the stringer elements;

Fig. 12 is a view similar to Fig. 11 showing a further modification;

Fig. 13 is an enlarged view showing still another method of securing the brackets upon the stringers;

Fig. 14 is a sectional view on line 14—14 of Fig. 13;

Fig. 15 is a front elevational view of a portion of a cabinet of modified form;

Fig. 16 is a sectional view on line 16—16 of Fig. 15;

Fig. 17 is a perspective view of an auxiliary compartment or "basket" employed in the cabinet;

Fig. 18 is a perspective view of another modification;

Fig. 19 is a sectional view on line 19—19 of Fig. 18;

Fig. 20 is a perspective view showing a modified form of hanger member;

Fig. 21 is a similar view showing a further modification;

Fig. 22 is a perspective view showing a modified form of hanger plates; and

Fig. 23 is a perspective view showing a vertical space divider.

To illustrate a preferred embodiment of my invention, I have shown in Fig. 1 of the drawings a cabinet comprising end supports or frame members 10 and 11 which may be constructed in any manner desired, but which will preferably be of sheet metal so as to be light in weight. These end sections may be held together either by the shelves themselves, as will be hereinafter explained, or, if desired, by suitable connecting members not shown. It will be understood that these end members may support the cabinet on the floor, counter or the like.

Mounted between these end supports and extending from one to the other are a plurality of shelves or tiers of compartments disposed one above the other and, while only two of such shelves are shown in the drawing, it will be understood that as many may be employed as are desired. These shelves each comprise a frame which consists of a pair of stringer elements 12 and 13 which, as shown in this modification of my invention, are of rod-like form and extend between the sections 10 and 11. The stringer elements 12 and 13 may be secured directly to the end sections, but preferably their ends are secured to cross members 14 and 15, thus forming a rectangular frame, the cross members in turn being secured to the end sections by bolts or the like 17 passing through the desired ones of a plurality of openings 18 provided in the end sections. Thus the frame and shelf as a whole are pivotally mounted between the end sections and

so may be disposed in a horizontal position as shown at the upper portion of Figs. 1 and 2 or in a tilted position as shown in the lower portion of these figures. Tightening of the bolts 17 will secure the shelves in any angular position to which they may be adjusted.

As shown in Fig. 2, the rods or stringer elements 12 and 13 are spaced vertically and also from front to back of the cabinet. With the 10 stringer elements thus disposed, they are adapted to have engaged therewith the ends of the hanger members or brackets which form the compartments for holding the boxed or unboxed articles.

These bracket members are shown in Figs. 4 15 and 5 of the drawings. That shown in Fig. 4 may be considered as the left-hand bracket member of a compartment and comprises a generally L-shaped flat body portion 19 provided with an outwardly projecting flange 20 standing at substantially right angles to the body portion. While, as shown, the legs of the bracket are at substantially right angles to each other, this disposition of the parts may be varied and the junction of the two portions may be rounded 25 or may be arranged at any desired angle. At their upper and lower ends, the two parts of the bracket are bent upon themselves as shown at 21 to provide loops to embrace the stringer elements 12 and 13. Adjacent their ends, tongues 30 22 may be stamped out of the body portion of the brackets for a purpose to be hereinafter described. Also as shown in Fig. 8, the body portions of the brackets are provided adjacent their ends with indentations 23 within which are openings 35 or perforations 24, and the bent ends 21 are likewise provided with registering openings 25.

The right-hand bracket 19a, shown in Fig. 5, is similar in all respects to the left-hand bracket 40 shown in Fig. 4, except that the flange 20 is omitted, this bracket merely being a flat piece of sheet metal bent into substantially L-shaped form and having its end portions constructed as already described in connection with the left-hand bracket shown in Fig. 4. As will be pointed out hereinafter, these brackets will be employed in pairs and, as two of them will be used between adjacent compartments, it is only necessary that one be provided with the partition flanges 20.

It will be obvious that these brackets may be engaged with the stringer elements 12 and 13, which in this form of my invention, are rods, by engaging the end portions of the brackets thereon, the brackets then being freely slidable upon the rods lengthwise thereof so that they may be placed in any adjusted positions to provide compartments of various widths. In order to secure the brackets in place, I have shown in Figs. 8, 9 and 10 a locking element consisting of an L-shaped member 26 having an offset cam portion 27 thereon and slots 28 cut therein, these slots lying opposite the cam portion 27. After the brackets have been placed upon the rods, this member may be inserted through the openings 24 and 25 with the cam portion 27 turned in a direction away from the rods. When the bracket has been moved to the desired position upon the rods, the member 26 is then given a partial turn 65 so as to cause the cam member 27 to engage the rod and frictionally bind the bracket thereto. At this time, the edges of the openings 24 and 25 will be received in the slots 28 so that the securing member 26 will be held firmly in place. Thus 70 the bracket member will be firmly secured in the

desired position along the rods 12 and 13. It will be understood that this applies to both ends of the bracket member.

In Figs. 11 and 12 of the drawings, I have shown modified forms of fastening elements which may be employed instead of the member 26. As shown in Fig. 11 of the drawings the opening 25 may be threaded for a machine screw 30 passed through the opening 24 and threadingly engaged with the opening 25, thus causing the looped end of the bracket to grip the rod 12. In Fig. 12 of the drawings a sheet metal screw 31 is employed in a manner similar to the screw 30 except that this screw will cut its own threads in the opening 25 and frictionally secure the brackets in place.

In Fig. 6 of the drawings I have shown a partition plate 32 designed to be detachably engaged with the flange 20 of the left-hand bracket shown in Fig. 4. This consists of a flat sheet metal member substantially rectangular in shape having tongues 33 and 34 struck therefrom along two sides and slightly displaced from the plane of the plate, so that these plates may be slipped upon the flanges 20 with the latter lying between the body of the plate and the tongues 33 and 34 and frictionally held in place so that this partition plate may be readily positioned upon or detached from the bracket.

It will be seen that the foregoing parts may be readily assembled without the use of special tools to form the completed cabinet which will usually be shipped to the customer in knocked-down condition. In assembling the device, the end sections 10 and 11 will be set up and may be secured together in any desired way. The rectangular frames comprising the stringer elements 12 and 13 and the connecting end pieces 14 and 15 will then be secured to these end members by the bolts 17 and the bolts tightened when this frame has been set at the desired angle. Then, beginning at the left-hand end of a shelf or a row of compartments as shown in Fig. 1, one of the left-hand brackets of Fig. 4 will be positioned adjacent the end member 14 and secured in place by one of the securing members shown in Figs. 8, 11 or 12. Next, one of the right-hand bracket members shown in Fig. 5 may be placed upon the rods 12 and 13 and, when it has been slidably moved along the rods to the desired position to provide a compartment of the proper width, it is secured in place. Immediately adjacent this bracket another left-hand bracket will be secured upon the rods 12 and 13, so that a compartment will be provided between the first left-hand bracket and the two brackets placed in close juxtaposition at a point spaced from the first, this compartment lying between flanges 20 at each side thereof. Thereafter, the brackets will be arranged in pairs along the rods 12 and 13 at desired positions, each pair consisting of a right- and a left-hand bracket, and each pair forming a new compartment with the pair at the left thereof. It will be seen that the body portions 19 and 19^a of the brackets form ledges upon which the boxes or packages 29 may rest and that the packages will be prevented from lateral movement by the flanges 20. If these flanges do not serve as sufficient partition members between two adjacent compartments, the members 32 may be placed upon the flanges 20 where desired, thus completely separating one compartment from another as shown in Fig. 3.

If it is desired to employ the cabinet in connection with unboxed merchandise or loose ar-

ticles, it will be necessary to close the space between the body portions 19 and 19^a of the brackets, and this may be done by the L-shaped or angle plates 35 shown in Fig. 7. These members 5 consist of relatively wide sheet metal members bent into angle shape and adapted to rest upon the ledges provided by the body portions 19 and 19^a of the brackets and, when put into place, will be confined laterally between the flanges 20. 10 The upper and outer edges may be engaged below the tongues 22 so that they will be held in place. This construction forms a bin open at the top and front into which small articles may be placed, and, if the shelf or row of bins is 15 tipped at a slight angle as shown in the lower portions of Figs. 1 and 2, the capacity of the bins will usually be ample, notwithstanding the fact that they are open at the front. Also the members 35 may be provided with small stuck-out tongues or ears 36 adapted to hold a card or the like to provide a label indicating the particular item contained in that bin or compartment. It will, of course, be understood that the plates 35 may be also used, if desired, when boxes or packages 20 are stored in the cabinet but, in many cases, it will be found that as the compartments may be formed of any desired width, the ledges provided between members 19 and 19^a will be sufficient to support the boxes or packages without 25 the use of the members 35. If it is desired to change the width of the compartments it is only necessary to loosen the fastening members 26, 30 or 31 and slide the brackets 19 and 19^a to the proper positions. 30 35 (In Figs. 13 and 14 of the drawings, I have shown a further method of securing the brackets to the stringer elements 12 and 13.) In this case, each of the brackets will be provided adjacent their ends with a tongue 38 struck from the 40 bracket and turned rearwardly as shown in Fig. 14 to cooperate with the rearwardly turned end 39 of the bracket to embrace therebetween the rod 12. The parts 38 and 39 are provided with outwardly turned ends 40 and 41 which may be 45 received within an oval or cam shaped opening 42 of a key 43. It will be apparent that when the key is in the position shown in Fig. 13, the ends 40 and 41 of the members 38 and 39 will lie in the narrow dimension of the slot 42 and, therefore, 50 be drawn together to cause the members 38 and 39 to frictionally grip the rod 12 and hold the brackets in place. If, however, the key 43 is turned to a position at right angles to that shown in Fig. 13, the members 40 and 41 will be permitted to spread apart, thus loosening the members 38 and 39 and permitting the bracket to 55 slide freely along the rod 12. The key 43 may be provided with a fingerpiece 44 so that it may be readily turned from one position to another. 60 In Figs. 15 and 16 of the drawings, I have shown a further modified form of my invention which differs from that previously described principally in the form of the stringer elements 12 and 13 and the manner of securing the brackets thereto. It will be understood that the brackets are of substantially the same form as those previously described, as are also the remaining parts of the structure. In this form of my invention the stringer elements 12 and 13 comprise channel shaped members 45 and 46 which may readily be formed of sheet metal strips bent into U-shaped form. The ends of the bracket members may be turned downwardly and rearwardly as 70 shown at 48 and 49 so that they may be inserted 75 within these channels and make a relatively close

frictional fit therein. Thus, they will normally be held in the proper position although they may be forcibly moved along the channels. If found necessary, means may be provided for securing the brackets in place such as binding screws or the like, although I have not disclosed such means herein.

It will be understood that as shown the rest of the structure of Figs. 15 and 16 is substantially the same as that shown in Figs. 1 to 7 and that the partition plates 32 may be employed as before. Sometimes, it is found necessary to provide a place for a few boxes or packages of relatively small size. To provide for such a contingency, I have shown a basket member in Fig. 17 which may be employed for this purpose. This member comprises a base or bottom portion 50 suspended by arms 51, and the material thereof folded over at their upper ends, as shown at 52, so that they may be hung over the partitions 32 to provide an auxiliary compartment in one of the main compartments to hold such small packages.

In Figs. 18 and 19 of the drawings I have shown a further modified form of my invention in which, instead of using sheet metal end members 10 and 11, I employ upstanding posts or rods 54 to provide supports for the shelves or rows of compartments. These posts may be supported and held together in any desired manner such, for example, as by bands 55. Secured upon these posts are stringer elements 56 which may be channeled or U-shaped members similar to the members 48 and 49 shown in Figs. 15 and 16, so that they provide channels to slidably receive the ends of the bracket members 57.

In this form of my invention, the stringer members 56 are slidably adjustable vertically on the posts 54 so that they may be secured in any desired position thereon, thus arranging the shelves as close together as desired. The stringer elements 56 may be provided with rearwardly turned end portions 58 as shown in Fig. 19 to embrace the post 54 and be secured thereto by the fastening elements 59 in a manner similar to that described in detail in connection with Figs. 8, 9 and 10. It will be appreciated that with this construction the stringer elements are universally adjustable on the members 54 and will not be limited to any set positions of vertical adjustment such as might be the case in the form of my invention shown in Figs. 1 and 2 wherein the vertical adjustment of the shelves or rows of compartments will be arranged by the bolt openings and the bolts 17.

While I have illustrated in Figs. 1 and 2 of the drawings a cabinet comprising end supports having a number of shelves, it will be understood that the invention is not limited in this respect. For example, the shelf structure described comprising a pair of stringer elements and hangers mounted thereon as described may be provided for use with existing end supports or cabinets. Also, a single shelf assembly may be employed upon an ordinary existing shelf to provide a proper place for each one of an assortment of different items.

It will also be understood that the stringer elements 12 may be polygonal in cross sectional shape instead of circular as shown or may be L-shaped or of angle iron construction. The hanger members, while shown as formed of sheet metal, may be cast or molded, or if an ornamental appearance is desired, may be formed of plastic material.

If desired, a tongue 22^a may be placed adjacent 75

the lower end of the hangers 19 and 19^a to cooperate with the upper tongues 22 to hold a label or card carrying appropriate indicia so that when the packages seat directly upon these hangers, the compartments may be properly labeled. If an angle plate 35 (Fig. 7) is employed, this tongue may be easily hammered flat so as to be out of the way and, in this event, the card will be placed on the angle plate and held by the tongues 36. It may here be noted that the angle plates may be made as high and as long as desired so as to make a bin of any desired depth, in which event openings would be made in the body of the plate to receive the tongues 22.

15 In Fig. 20 of the drawings I have shown a hanger element of modified form to be used between adjacent compartments instead of a pair of hanger members 19 and 19^a as previously described. This member is substantially L-shaped 20 in form comprising the body portions 61 and 62 which are relatively wide as compared to the hanger members 19 and 19^a, and flanges 63 and 64 are provided intermediate the side edges of the portions 61 and 62, so that supporting ledges 25 are provided on each side of the flanges. The ends of this member are folded back as shown at 65 and 66 to receive the stringer elements, and openings 67 are provided so that it may be secured in place by any of the fastening means shown in 30 Figs. 8, 11, 12 or 14. Also, tongues 68 and 68^a are provided as before to cooperate with one of the angle brackets shown in Fig. 7 to support label cards.

In assembling a shelf employing these devices, 35 one of the single brackets shown at 19 in Fig. 4 would be employed at the left-hand end of the shelf, then a number of the double brackets shown in Fig. 20 would be placed along the stringer elements in spaced relation as described and secured 40 thereto to form partitions between the compartments and provide supporting ledges on each side of the partition. At the right-hand end of the shelf, another bracket 19 could be employed, this, however, being a right-hand bracket with the 45 flange on the side opposite that shown in Fig. 4. If the sides of the bracket 19 are of equal length, it could simply be inverted to form a right-hand bracket.

In Fig. 21 of the drawings I have shown a hanger 50 member which could be employed to form stepped shelves or a plurality of shelves of less depth between a single pair of stringer elements. As shown, this hanger member comprises a plurality of vertical portions 70 and a plurality of horizontal portions 71, the ends of the hanger being arranged as before so that they may be readily secured to the stringer elements. Adjacent one edge of each of the portions 70 and 71 are flanges 72, this bracket corresponding to the left-hand bracket shown in Fig. 4. The corresponding right-hand bracket would be similarly formed except that the flanges 72 would be omitted. If desired, this stepped hanger could likewise be made as a double hanger similar to that shown in Fig. 20.

In Fig. 22 of the drawings, I have shown an angle plate 73 which may be employed to form the bottom and back of a bin in place of the angle plate shown in Fig. 7. In this instance the angle plate is provided with a front side or lip 74 which may be of any height desired in order to form a bin of the desired depth. This will, of course, increase the depth of the bin which is formed over that which might be formed with the plate 70 shown in Fig. 7.

In some instances, it is advantageous to employ a vertical space divider so as to divide a compartment vertically. This is expedient where only a few articles of a kind are kept in stock and will, in effect, make two compartments of the same width where one previously existed. Such a vertical space divider is shown in Fig. 23 and comprises a member 75 having a looped end 76 by which it may be secured to a stringer element and also provided with a longitudinal slot 77. An L-shaped member 78 is adjustably secured to the member 75 by bolts 79 passing through the slot 77. This member 78 is wider than the member 75 so that, while the loop 76 will engage the stringer element at one side of the portion 21 of a hanger member 19, the member 78 will project over the body of the hanger 19 and provide a horizontally extending supporting ledge 80. As shown in Fig. 23 where the hanger 19 is illustrated in dotted lines, the horizontal ledge portion 80 of this member is provided with a flange 81 which will form a side support for the packages thereon. It will be seen that the horizontal portion 80 of this member will lie substantially parallel to the lower horizontal portion of the hanger member 19 but spaced upwardly therefrom so that an upper and a lower shelf will be provided by the two hangers. It will be understood that it is contemplated to also provide a second vertical space divider similar to that shown in Fig. 23, except that the flange 81 and the member 75 will be in reversed positions, as to left and right, so that this second member may be used at the right side of a compartment while the divider of Fig. 23 will stand at the left.

While I have shown and described some preferred embodiments of my invention, it will be understood that it is not to be limited to all of the details shown, but is capable of modification and variation within the spirit of the invention and within the scope of the claims.

What I claim is:

1. A storage or display cabinet comprising upright end supports, a pair of stringer elements extending between said supports, partition members, means supporting said partition members on said elements in spaced relation for adjustment longitudinally thereof to form compartments of various widths between the partition members, and means pivotally securing said stringer elements in pairs to said end supports.

2. A storage or display cabinet comprising upright end supports, stringer elements extending between said supports, means carried by said stringer elements providing compartments, said means comprising a plurality of spaced hanger members supported by said stringer elements and adjustable longitudinally thereof, said members having flat body portions forming supporting ledges at each side of a compartment, flat plate-

like supporting members resting against said ledges, and means for securing said hanger members to the stringer elements in adjusted position.

3. A storage or display cabinet comprising upright end supports, stringer elements extending between said supports, means carried by said stringer elements providing compartments, said means comprising a plurality of spaced L-shaped hanger members supported by said stringer elements and adjustable longitudinally thereof, said members having flat body portions forming supporting ledges at each side of a compartment, and L-shaped members resting against said ledges, each portion of one of said members being of flat plate-like form.

4. A storage or display cabinet comprising upright end supports, stringer elements extending between said supports, means carried by said stringer elements providing compartments, said means comprising a plurality of spaced hanger members detachably secured to the stringer elements and adjustable lengthwise thereof, and means securing said members in adjusted positions, said securing means comprising a cam member movably mounted on a hanger member and frictionally engaged with a stringer element.

5. A storage or display cabinet comprising upright end supports, stringer elements extending between said supports, means carried by said stringer elements providing compartments, said means comprising a plurality of spaced hanger members supported by said stringer elements and adjustable longitudinally thereof, said members having flat body portions forming supporting ledges at each side of a compartment, and L-shaped members resting against said ledges, each of said L-shaped members having a back portion and a bottom portion of flat plate-like form and a front lip portion.
